DESIGN FOR A GRAND PIANO

Paul von Rohl, St. Paul, Minn.

Application June 3, 1936, Serial No. 62,983

Term of patent 7 years

To all whom it may concern:

Be it known that I, Paul von Rohl, a citizen of the United States, residing at St. Paul, county of Ramsey, and State of Minnesota, have invented a new, original, and ornamental Design for a Grand Piano, of which the following is a specification, reference being had to the accompanying drawing, forming part thereof:

The dominant feature of the design is shown in full lines in the drawing.

I claim:

The ornamental design for a grand piano as shown and described.

PAUL VON ROHL.
